UNITED STATES PATENT OFFICE

RUDOLPH DOPYERA, OF LOS ANGELES, CALIFORNIA

DESIGN FOR A COVER PLATE FOR MUSICAL INSTRUMENTS

Application filed December 4, 1931. Serial No. 41,963. Term of patent 14 years.

To all whom it may concern:

Be it known that I, RUDOLPH DOPYERA, a citizen of the Republic of Czechoslovakia, and residing at Los Angeles, in the county of Los Angeles and State of California, have invented a new, original, and ornamental Design for a Cover Plate for Musical Instruments, of which the following is a specification, reference being had to the accompanying drawings, forming a part thereof.

In the accompanying drawings Figure 1 is a top plan view showing my invention.

I claim:

The ornamental design for a cover plate for musical instruments substantially as shown.

RUDOLPH DOPYERA.
